UNITED STATES PATENT OFFICE

2,541,732

APPARATUS FOR CONTROLLING THE HARDNESS OF WATER

Fred Carl Wilhelm, Minneapolis, Minn.

Application March 3, 1947, Serial No. 732,104

3 Claims. (Cl. 210—16)

1

This invention relates to new and useful improvements in apparatus for controlling the hardness of water, and more particularly to such a device adapted for use in conjunction with a steam boiler to regulate and control the hardness of the water delivered thereto.

It is well known in the operation of steam boilers that it is of the utmost importance to control the hardness of the water delivered to the boiler in order to prevent damage to the boiler from foreign matter which may be contained in the hard water. It is, therefore, more or less common practice to provide means for controlling the hardness of the water delivered to the boiler whereby maximum efficiency and long life of the boiler may be obtained.

Numerous devices have heretofore been devised for controlling the hardness of the water delivered to a boiler, but to the best of my knowledge, all of these have been rather expensive and costly to install and maintain, and some are rather complicated to operate.

The novel device herein disclosed is a result of considerable experimental and research work in an attempt to provide a simple, inexpensive device which may be readily and conveniently installed in the usual feed line of a boiler, and into which zero soft water and hard water are introduced and intermixed in such a manner that the resultant water mixture discharging from said device will have a predetermined hardness or pH value of 9.6 or over, thereby assuring that the carbonate-sulphate content of the water will be balanced, so that the water delivered to the boiler will have no damaging effects upon the boiler or other equipment to which it may be supplied.

A further object is to provide a simple and inexpensive device for controlling the hardness of water delivered to a boiler, which comprises a housing whose walls define a mixing chamber, and said housing having an inlet for zero soft water and one for hard water and being provided with a single outlet, and means being embodied in the housing for controlling the flow of hard water thereinto whereby the hardness of the water flowing from the device to the boiler may be accurately controlled.

A further and more specific object is to provide a device for controlling the hardness of water delivered to a boiler or other apparatus to be supplied with steam having a known hardness, which comprises a simple inexpensive housing having an inlet for zero soft water and an inlet for hard water, and a single outlet for the

2

discharge of the treated water therefrom, and the member being rotatably received in one end of the housing and having a sleeve-like portion fitting into the cylinder and provided with a plurality of metering orifices of different diameters adapted to be selectively moved into registration with the hard water inlet, whereby the flow of hard water into the housing may be accurately controlled so as to control the hardness of the water discharging from the housing through its outlet to the boiler, and means being provided whereby said member may be conveniently rotated to vary the volume of hard water delivered into the housing.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a longitudinal sectional view through the device showing the general construction thereof;

Figure 2 is a sectional view on the line 2—2 of Figure 1;

Figure 3 is an end view of Figure 1, showing the means for varying the supply of hard water into the housing;

Figure 4 is a perspective view of the sleeve-like member removed from the housing; and

Figure 5 is a schematic diagram showing the device interposed into the usual water feed line of a steam boiler.

The novel device herein disclosed is shown comprising a housing, generally designated by the numeral 2, having a closed end 3 provided with a threaded aperture 4 adapted to receive one end of a pipe 5 which may lead from a suitable condensate tank 6 of a conventional water softening plant or apparatus, as will be understood by reference to Figure 5.

The opposite end of the housing 2 is shown provided with a cylindrical bore 7 into which is fitted a sleeve-like portion 8 of a closure member 9 secured in adjusted position to the housing by suitable cap screws or bolts 11, as shown in Figures 1 and 3.

A hard water inlet 12 is provided in the upper portion of the housing 2 and is threaded to re-

ceive one end of a pipe 13 whose opposite end may be in communication with a pipe 14 leading from a suitable source of hard water supply, such as a deep well, indicated by the numeral 15 in Figure 5.

The opposite end of the pipe 14 is shown connected to the upper end of a suitable water softener 16, having a soft water discharge pipe 17 for conducting the soft water from the water softener 16 to the condensate tank 6, as indicated in Figure 5.

By reference to Figure 1, it will be noted that the housing 2 has a discharge opening 18 to which one end of a suitable pipe 19 is connected which leads from the housing 2 to a boiler 21 to be supplied with treated water. A suitable feed pump 22 may be interposed in the feed pipe 19 to assure a uniform supply of water to the boiler 21. The zero soft water pipe 5 and the discharge pipe 19 are preferably of substantially the same diameter, whereas the hard water supply pipe 13 may be relatively smaller. The hard water pipe 13, however, is amply large to supply the necessary volume of hard water for all occasions.

An important feature of the present invention resides in the means provided in the housing 2 for controlling and regulating the supply of hard water into the chamber 23, defined by the walls of the housing. The means provided for thus controlling the flow of hard water into the mixing chamber 23 is shown comprising a series of apertures 24, 25, 26 and 27, provided in the sleeve-like portion 8 of the closure member 9 and spaced equi-distant apart around the circumference of the sleeve-like portion 8, as best shown in Figure 2. The axes of the apertures 24 to 27, inclusive, and the axis of the feed pipe 13 are disposed in a common plane, whereby said apertures may be selectively moved into registration with the hard water pipe 13 by simply rotating the closure member 9, after having removed the cap screws 11.

But two cap screws are shown in the drawing, whereas 4 tapped holes 28 are provided in the adjacent edge of the wall of the housing. By this arrangement the closure member 9 may be adjusted in steps of 90°, the equivalent of the spacing between the apertures 24 to 27.

It will be noted by reference to Figure 3 that the outer face of the closure member 9 is provided with suitable indicia, generally designated by the numeral 29, which may be in the form of numerals 10—16—21—30, which correspond, respectively, to the apertures 27, 26, 25, and 24. In other words, when the numeral 21 is positioned at the top in line with the hard water pipe 13, as shown in Figure 3, the next to the smallest aperture 25 will be in registry with the hard water pipe 13, as shown in Figure 2.

When the sleeve-like member has been adjusted to its proper position, the cap screws 11 are secured in place to secure the closure member 9 to the housing. A suitable gasket 31 is preferably provided between the adjacent end of the housing 2 and the closure 9 to prevent leakage between said parts.

Another feature of the invention resides in the means provided whereby the treated or softened water flowing from the casing 2 to the boiler 21 may readily be checked from time to time to ascertain its hardness.

To thus check the water flowing through the pipe 19 from the mixing chamber of the device, a small test cock 32 is mounted in the pipe 19, preferably adjacent to the casing 2 of the device,

whereby samples of water flowing through the pipe may be withdrawn therefrom at any time for testing purposes.

By reference to Figure 5, it will be noted that a steam supply pipe 33 leads from the top of the boiler to the equipment or apparatus to be supplied with steam, generally designated by the numeral 34 in the drawings. A return pipe 35 leads from the steam supplied equipment 34 to the condensate tank 6, as shown. By the use of the novel water proportioning device herein disclosed, the hardness or pH value of the raw or fresh water delivered to a steam boiler, may be accurately and automatically controlled at all times. In carrying out the method herein disclosed, a portion of the hard water received from the well 15 is delivered to the water softener 16 from whence softened water is delivered into the condensate tank whereby the water before being delivered into the housing 2 of the present invention, is reduced to zero hardness.

As this zero soft water is delivered into the housing through the pipe 5, a measured flow of hard water is simultaneously delivered into the chamber 23 to mix with the zero soft water, the flow of hard water into the chamber being controlled by manipulation of the closure member 9, whereby the resultant water mixture flowing from the chamber 23, through the pipe 19 to the boiler may be of the desired hardness.

Once the novel device herein disclosed has been embodied in a boiler system, as indicated in Figure 5, and the sleeve-like portion 8 of the closure 9 has been adjusted to cause the flow of hard water delivered into the mixing chamber 23 to produce the desired pH value of the water flowing from the device to the boiler, no further adjustment may be necessary, and the device will operate efficiently and automatically for an indefinite period.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. In a device adapted for use in conjunction with a steam boiler to control the hardness of the water delivered thereto, said device comprising a housing open at one end and having a single outlet adapted to be connected to the water supply pipe of a boiler, a pipe connected to the opposite end of said housing for delivering zero soft water thereto, a hard water supply pipe in communication with the interior of the housing adjacent to the open end thereof for delivering raw hard water thereto, a cap-sleeve adjustably secured in the open end of said housing and having a sleeve fitting into the housing in overlapping relation to the intake of the hard water pipe, and a plurality of different sized apertures in said sleeve adapted to be selectively moved into registration with the hard water pipe by relative rotation of the sleeve, thereby to vary the flow of hard water into the housing and whereby the hardness of the water flowing from said housing to the boiler may be accurately controlled.

2. In a device adapted for use in conjunction with a steam boiler to control the hardness of the water delivered thereto, said device comprising a housing having a discharge outlet in its lower portion adapted to be connected to the water supply pipe of a boiler, a pipe connected to one end of said housing for delivering zero soft water thereto, a hard water supply pipe in communication with the interior of the housing adjacent to the open end thereof for delivering hard water thereto, a cap-sleeve adjustably secured to the open end of said housing and having a sleeve fitting into the housing in overlapping relation to the intake of the hard water pipe, a plurality of different sized apertures in said sleeve spaced equi-distant apart around its circumference, means whereby said cap-sleeve and sleeve may be operated to selectively move said apertures into registration with the hard water pipe to vary the flow of hard water into the housing and whereby the regulated flow of hard water may thoroughly intermix with the zero soft water delivered to the housing to accurately control the hardness of the water delivered to the boiler.

3. In a device adapted for use in combination with a steam boiler for controlling the hardness of water delivered thereto, said device comprising a housing forming a chamber having spaced-apart independent soft and hard water inlets and a single outlet through which water may flow from said device to the boiler, said housing being open at one end, a closure for the open

end of the housing having a sleeve fitting into said housing beyond the inlet of the hard water supply pipe, and a series of different size openings in the closure flange adapted to be selectively moved into registration with the hard water pipe, upon installation of the device with a given boiler, whereby the delivery of hard water into the housing may be so regulated that when intermixed with the zero soft water delivered thereto, the water discharging from the housing to the boiler will have the required degree of hardness for each given boiler installation.
